UNITED STATES PATENT OFFICE.

GEORGE H. DODGE, OF PHILADELPHIA, PENNSYLVANIA.

GRIPPING DEVICE FOR CABLE CARS.

SPECIFICATION forming part of Letters Patent No. 340,034, dated April 13, 1886.

Application filed January 25, 1886. Serial No. 189,643. (No model.)

To all whom it may concern:

Be it known that I, GEORGE H. DODGE, a citizen of the United States, residing in Philadelphia, Pennsylvania, have invented certain 5 Improvements in Gripping Devices for Cable Cars, of which the following is a specification.

My invention relates to improvements in gripping devices for cable railways; and the main object of my invention is to move the 10 bars horizontally from and toward each other, one acting on cams on the other, causing them to grip or release the cable.

In the accompanying drawings, Figure 1 is a side view of my improved gripping device, 15 showing the same open. Fig. 2 is a side view showing the same closed onto the cable. Fig. 3 is a section on the line 1 2, Fig. 2; and Figs. 4, 5, 6, and 7 are views showing modifications of my invention.

20 A B are two flat bars secured at their upper ends to nuts *a* *b* through the medium of devices which I will describe hereinafter, these devices being intended to allow lateral play of the bars. To these nuts is adapted the 25 screw-shaft C, having right and left handed threads, the right-handed thread being adapted to the nut *a* and the left-handed thread to the nut *b*. The screw-shaft C is free to turn in suitable bearings, *c*, secured to a plate, X, 30 bolted to the frame-work of the car.

At the lower end of the bar A is a box, D, and at the lower end of the bar B is a box, E. The box D carries a series of cams, F, which are pivoted by a pin, *f*, to the side cheeks, *d*, 35 of the box, and said box slides in the box E, the latter having a portion, *e*, projecting under the cams F and forming a bearing for the cable *x*. A lip, *e'*, forming part of the box E, projects over the upper part of the box D, and 40 serves to keep the boxes always in line with each other. On each cam F, at or about the point indicated in the drawings, is a pin, *g*, which passes through a slot, *h*, in the box E, the box D being recessed at this point to allow 45 for the free passage of the pin.

When the parts are in the position shown in Fig. 1, the grip is open, but by turning the screw-shaft C in the direction of its arrow the nuts *a* *b* will be drawn toward each other, and 50 movement in reverse directions will be im-

parted to the boxes D E, and the cams F, being pivoted to the box D and governed by the slots *h* in the box E, will gradually close on the cable as the screw is turned, thus firmly gripping the cable.

It will be seen that I do not rely upon the moving cable to insure the movement of the cams into the position for gripping said cable, the movement of the cams being wholly under control of the screw.

When the cable is gripped, the cams will be in the position shown in Fig. 2. By reversing the movement of the screw-shaft C the boxes D E will be moved apart, thus forcing the cams clear of the cable, as in Fig. 1.

The nuts *a* and *b* have arms *m m*, through slots *n* in which pass flat bars N, secured to the upper ends of the bars A B and suitably braced by bars *p p*, (see Fig. 3,) this construction permitting lateral play of the bars D 70 without straining the plate X. Each nut *a* *b* has a fin, *s*, fitting into a groove, *t*, in the plate X, forming the base of the bearing-blocks C, the nuts being thereby prevented from turning with the screw-shaft.

In the modification shown in Figs. 4, 5, and 6 both boxes are provided with gripping-cams, portions of the cams of one box being adapted to recesses in part of the other box, these recesses being such that each cam is 80 confined between lugs *h' h'*, so that the cams can be swung in one direction or the other by the lateral movement of the boxes. (See Fig. 6.)

The cams F may be modified in shape, as 85 shown in Fig. 7, for instance.

I claim as my invention—

1. The combination of the boxes D E, movable in opposite directions, with cable-gripping cams hung to one box and having portions engaging with the other box, all substantially as specified.

2. The combination of the boxes D E, movable in opposite directions, a cable-support on said box E, and cable-gripping cams hung 95 to the box D and operated by engagement with the box E, all substantially as specified.

3. The combination of the boxes D E, cable-gripping cams hung to one box and having portions engaging with the other box, and a 100

right-and-left screw and nuts, whereby the boxes are caused to move in opposite directions, all substantially as specified.

4. The combination of the nuts and the
5 right-and-left screw for operating the same,
with bars A B, carrying gripping mechanism
and hung to bars N, free to slide laterally in
the nuts, all substantially as specified.

In testimony whereof I have signed my name
to this specification in the presence of two sub- 10
scribing witnesses.

GEORGE H. DODGE.
